COVERED SAUCEPAN

Gerald Gulotta, New City, N.Y., assignor to J. C.
Penney Company, Inc., New York, N.Y.

Filed Apr. 26, 1972, Ser. No. 247,922

Term of patent 14 years

Int. Cl. D7—02

U.S. Cl. D7—95

FIG. 1

FIG. 2

FIG. 3

FIG. 4

FIG. 5

FIG. 6

FIG. 7

FIG. 8

FIG. 9

FIG. 10

FIG 1 is a top plan view of a covered saucepan showing my new design;

FIG. 2 is a side elevation view thereof;

FIG. 3 is a bottom plan view thereof;

FIG. 4 is a front end view thereof;

FIG. 5 is a rear end view thereof;
FIG. 6 is a top plan view of a modified form of the covered saucepan shown in FIG. 1 wherein a pouring spout is formed in the rim;

FIG. 7 is a side elevation view of FIG. 6;

FIG. 8 is a bottom plan view of FIG. 6;

FIG. 9 is a front end view of FIG. 6; and

FIG. 10 is a rear end view of FIG. 6.

I claim:

The ornamental design for a covered saucepan, substantially as shown and described.
